[57] CLAIM

The ornamental design for a portable order terminal with printer, as shown and described.

DESCRIPTION

FIG. 1 is a top, front, right side perspective view of a portable order terminal with printer showing our new design;

FIG. 2 is a top, front, right side perspective view of a second embodiment thereof, the attachment is shown in broken lines for illustrative purposes only and forms no part of the claimed design;

FIGS. 3 and 4 are top plan views of the first and second embodiments thereof respectively on an enlarged scale; FIGS. 5 and 6 are right side elevational views of the first and second embodiments thereof respectively on an enlarged scale;

FIG. 7 is a left side elevational view thereof on an enlarged scale;

FIG. 8 is a bottom plan view thereof on an enlarged scale;

FIG. 9 is a front elevational view thereof on enlarged scale;

FIGS. 10 and 11 are rear elevational views of the first and second embodiments thereof respectively on an enlarged scale.

The bottom plan view, left side elevational view and the front elevational view are identical in both embodiments.
